CONSTANT PRESSURE SPRINKLER

Filed Oct. 25, 1943

FIG. 1.

UNITED STATES PATENT OFFICE

2,380,101

CONSTANT PRESSURE SPRINKLER

Orton H. Englehart, Glendora, Calif.

Application October 25, 1943, Serial No. 507,501

3 Claims. (Cl. 299—69)

My invention relates to a constant pressure sprinkler and the subject matter herein shown described and claimed, is a continuation-in-part of my co-pending application for patent on Self regulating sprinkler, filed July 31, 1940, Ser. No. 348,672.

The principal object of my present invention is, to provide a constant pressure sprinkler and which rotates with a step by step movement as a result of repeated impacts of a spring actuated pivoted element, with simple and effective means for bringing about and maintaining a stable step by step forward rotation of the jet nozzle and associated parts, regardless of the elevation of the rotating jet nozzle in relation to the part upon which it is mounted.

With the foregoing and other objects in view, my invention consists in certain novel features of construction and arrangement of parts which will be hereinafter more fully described and claimed and illustrated in the accompanying drawing, in which:

Fig. 1 is a vertical section taken through the center of my improved sprinkler.

Fig. 2 is a horizontal section taken on the line 2—2 of Fig. 1.

Fig. 3 is a horizontal section taken on the line 3—3 of Fig. 1.

Fig. 4 is a horizontal section taken on the line 4—4 of Fig. 1.

Fig. 5 is a horizontal section taken on the line 5—5 of Fig. 1.

Fig. 6 is a horizontal section taken on the line 6—6 of Fig. 1.

Referring by numerals to the accompanying drawing, which illustrates a preferred embodiment of my invention, 10 designates the sprinkler head carried by the upper end of a tubular spindle 11 which is mounted to rotate and slide vertically through the upper portion of a tubular member 12 and the latter being mounted on an upright water supply pipe 13.

The upper portion of member 12 provides a bearing 12^a for spindle 11 and formed in the lower portion of said member 12 is a chamber 14 within which is fixed, a concentrically arranged tube 15, the upper portion of which provides a bearing for the lower portion of spindle 11.

Formed through the wall of tubular spindle 11 are apertures 16, which, when the sprinkler is at rest, occupy positions just below the lower end of the bearing 12^a, as illustrated in Fig. 1 and thus the duct through the tubular spindle

is in communication with chamber 14 in member 12.

Seated in the center of the closed lower end of spindle 11 is a screw 17 and formed through said closed lower end around said screw are ports 18.

Swiveled upon the lower end of screw 17 is a cup washer 19 and secured thereto is the upper end of a retractile spring 20, which is suitably connected to the upper end of screw 21 and the latter being seated in a plug 22, which is removably seated in the lower end of tube 15. Screw 21 carries a lock nut 23.

Projecting outwardly and upwardly from the side of sprinkler head 10 is a jet nozzle 24 and mounted to swing in a horizontal plane on a pin 25 which projects upwardly from said head, is an arm 26 carrying on its forward end an inclined vane or blade 27.

This vane is preferably a compound vane or a combination of a vane and spoon as illustrated and described in detail in U. S. Letters Patent #1,997,901 issued to me April 16, 1935.

As arm 26 oscillates on its axis, the side of vane 27 intermittently strikes against a lug 24^a which projects outwardly from the side of nozzle 24 thereby moving same a short distance, and when in contact with said nozzle said vane is in the path of travel of the jet issuing from said nozzle as illustrated in Fig. 2.

Detachably secured to the upper end of pin 25 is a washer 28 to which is secured the upper end of a torsional spring 29, the lower end thereof being connected to arm 26, so as to yieldingly resist the outward swinging movement of the forward, vane-carrying end of said arm.

The rear end of arm 26 carries a weight 30 which counterbalances the weight of vane 27.

In order to produce and maintain a stable step by step movement for the sprinkler head, I provide frictional means between said head and the upper portion 12^a of member 12, such means including an open resilient ring 31, which is sprung onto the upper end of portion 12^a so as to engage same with a certain degree of friction and one end of this spring projects outwardly to form a finger 32.

Secured to head 10 is the upper end of a plate 33, the depending bifurcated lower portion 34 of which receives finger 32, and thus operative engagement between the parts is provided regardless of the elevated position of the sprinkler head. (See Fig. 3.)

In order to minimize leakage through the joint between tubular spindle 11 and its bearing 12^a, said spindle within said bearing may be provided

with an annular groove 35 having communication with the duct through tubular spindle and the chamber 14 in member 12 and which arrangement is more fully set forth in my aforementioned co-pending application Ser. No. 348,672.

In the operation of my improved constant pressure sprinkler, spindle 11, head 10 and parts carried thereby are elevated by pressure of the water entering chamber 14 from supply pipe 13 and as such movement occurs, the openings 16 enter the bearing in part 12^a thereby gradually restricting water flow through said openings until the pressure in the chamber within tube 15 below spindle 11 exerts an upward thrust on said spindle to equal the weight of the sprinkler head unit, plus the pull of spring 20, which opposes upward movement of the spindle.

The tension of spring 20 may be adjusted by means of screw 21 so as to establish a balance or equilibrium point at the desired pressure.

Ports 18 permit pressure to pass from the duct in spindle 11 into the chamber in member 15 below said spindle. The jet of water issuing from nozzle 24 impinges against vane 21 thereby swinging same outwardly a short distance and as said vane swings inwardly under the influence of spring 29, it strikes against lug 24^a on the side of the nozzle thereby causing head 10 to rotate a short distance in its bearing 12^a.

Thus, as the movements just described are repeated, the sprinkler head and nozzle are rotated with an intermittent or step by step movement. Such movement is controlled and rendered stable by the frictional engagement of spring 31 with member 12^a and the provision of the bifurcated arm 33 and finger 32 received thereby, enables the frictional means to function regardless of the elevation of the tubular spindle and parts carried thereby.

Where the sprinkler is constructed to move clockwise, spring 31 is arranged on bearing 12^a so that, as the sprinkler moves backward under the torsional stress of the outwardly swinging arm 26, it is checked by the tightening of spring around said bearing and upon reverse or clockwise movement of the arm and sprinkler the spring is loosened upon its bearing, thereby per-

mitting relatively free rotation of the head 10 and parts carried thereby.

Thus it will be seen that I have provided a constant pressure sprinkler which is simple in structure, inexpensive of manufacture and very effective in performing the functions for which it is intended.

It will be understood that minor changes in the size, form and construction of the various parts of my improved constant pressure sprinkler may be made and substituted for those herein shown and described without departing from the spirit of the invention, the scope of which is set forth in the appended claims.

15 I claim as my invention:

1. In a constant pressure water sprinkler, a tubular spindle, a sprinkler head mounted on said tubular spindle, means mounted on said sprinkler head and actuated by the water discharging from said head for imparting step by step rotary movement to said head and spindle, a support in which said spindle is mounted for rotary movement, said support having a chamber, there being an opening formed in said spindle and adapted to communicate with the opening in said support, the effective size of which opening is restricted as the spindle moves upwardly through said support with means for yieldingly resisting the upward movement of said spindle.

2. A constant pressure water sprinkler as set forth in claim 1 and means for adjusting said yielding resistance means.

3. In a constant pressure water sprinkler, a hollow support having a bearing, means for delivering water under pressure to said support, a tubular spindle mounted for rotation in said bearing, a sprinkler head mounted on said tubular spindle, swinging means actuated by the water discharging from said head for imparting step by step rotary movement to said head and spindle and cooperating means between said support and said spindle for yieldingly resisting the movement of said swinging means in one direction and for permitting free movement of said swinging means 45 in the opposite direction.

ORTON H. ENGLEHART.
